UNITED STATES PATENT OFFICE.

ERRETT S. RHOADS, OF KANSAS CITY, MISSOURI.

CONCRETE-BLOCK-CASTING CAR.

Application filed August 18, 1926, Serial No. 129,897. Renewed September 19, 1927.

This invention relates to concrete block casting cars of that class for forming supports for forms used in producing such concrete blocks or units, as exemplified by U. S. Patent No. 1,532,924, issued April 7, 1925, to W. E. Nelson, under which and other patents for related inventions also issued to said Nelson, I hold the exclusive rights to certain territory. It has been found through the use of cars of the character above mentioned, made under said patent, that warpage or distortion soon occurs and substantial replacements or repairs must be resorted to for the production of uniform and interchangeable units or blocks, and that, irrespective of the kind of material employed in the building of such cars, frequent and material replacements and repairs cannot be avoided. I have found that the difficulties mentioned are due to a rigidity of relation between the bottom and walls or gages, and are almost entirely overcome by supporting the walls of the car independent of or in a play relation to the bottom of the car.

My object therefore, is to produce a car comprising a base frame, and a bottom and walls supported from said frame independently of each other and bearing a play relation, so that no such general distortion or warpage can occur as to necessitate the substantial rebuilding of the car, minor repairs or replacements being possible at low cost and expeditiously to permit the car to be used without material impairment of service.

With the general objects mentioned in view, the invention consists of certain novel and useful features of construction and combinations of parts as hereinafter described and claimed; and in order that it may be fully understood, reference is to be had to the accompanying drawings, in which:

Figure 1 is a plan view of a concrete casting car body embodying the invention.

Figure 2 is a section on the line II—II of Figure 1.

Figure 3 is a section on the line III—III of Figure 1.

Figure 4 is a section on the line IV—IV of Figure 1.

Figure 5 is a fragmentary section of a part of the car body equipped with a different type of clamping mechanism from that shown in the other figures.

Referring now to the drawings in detail, 1 indicates a longitudinal stringer and 2

inverted angle bars extending parallel with and at opposite sides of and equal distances from the stringer. 3 indicates a plurality of transverse angle bars fastened upon the stringer and resting upon the inverted angle bars and projecting substantially beyond one of the latter. Sectional longitudinal blocks 4 are suitably secured to the angle bars 2 at one end thereof, and wear plates 5 are secured upon said blocks, the latter being of less depth than the angle bars 3 so that the wear plates shall offer no obstruction to the support of the bottom, hereinafter identified, of the body of the car. 6 are secured to the under side of the blocks 4 and are provided with depending perforated arms 7 for the pivotal support of the clamping mechanism hereinafter described. Vertical ledger plates 8 are secured to the opposite ends of angle bars 2 from the blocks 4, and angle-plate upright or posts 9 are secured to said ledger plates to form a support for a fixed end wall or gage 10 for the body, this end wall or gage being disposed above and spaced at a substantial distance from the angle bars 2.

A side wall or gage 11 overlaps one end of gage 10, and is supported in the same horizontal plane as gage 10 by vertical angle-plates or posts 12 secured to ledger plates 13 fastened to the projecting ends of transverse angle bars 3.

A series of transverse timbers 14 rest upon and are suitably secured to the longitudinal angle bars 2, the timber adjacent the right hand end of said angle bars spacing the sections of the short blocks 4, and being notched (not detailed) to accommodate the wear plates 5.

The bottom of the body comprises a series of planks 15 or the like, extending longitudinally and fastened down upon the cross timbers 14, the upper side of the bottom standing flush with the lower edges of the gage rails and terminating adjacent the inner faces of said rails. The bottom at the other end, is interposed between the underlying timber 14 and a movable gage or clamp wall 16 paralleling gage or wall 10. The movable gage or wall is provided with a socketed bracket 17 engaged by the ends, in Figures 1 to 4 inclusive, of clamping screws 18 adapted preferably for operation by hand. The clamp screws are mounted in the upper ends of angle brackets 19 mounted on pivots 20 in perforations of the depend-

ing arms 7, the arrangement being such that the proper operation of the clamping mechanism forces the clamping gage or wall 16 bodily toward the fixed gage or wall 10 to apply endwise pressure on the casting or molding elements, not shown, for use upon the casting car, which casting or molding elements form no part of this invention and hence are not described or shown in full lines. To insure the operation of the clamping mechanism, hooks 21 are pivoted upon the wear plates 5 for engagement with the outer edges of the angle brackets 19 to form resistance points to the force exerted in the clamping operation, upon the gage or wall 16.

The ends of certain of the cross timbers 14 at the opposite sides of the bottom from gage rail 11, are notched in their upper sides for the accommodation of wear plates corresponding to wear plates 5, and bolts used to secure the wear plates to the said timbers 14, are also employed for fastening underlying brackets in place corresponding to brackets 6.

A movable side wall or gage 23 overlies the bottom 15, and is equipped with socketed brackets 24 for engagement by clamping screws 25, mounted in angle brackets 26 pivotally mounted on the plates corresponding to plate 6, and hooks 27 mounted on the plates corresponding to wear plates 5, engage brackets 26 to perform the same function for gage or wall 23 as that performed by brackets 19 for gage or wall 16, during the clamping operation, the gage or wall 23 applying sidewise clamping pressure on the casting or molding forms hereinabove mentioned.

As another and perhaps more satisfactory means for clamping the movable gages or walls in place, I may mount cam levers 28 in the pivoted brackets at the sides and ends of the body, so that the operation of said cam levers shall apply the clamping pressure, and to hold the cam levers against slippage, I have provided supplemental co-operating cams 29 mounted in the upper ends of said pivoted brackets, to engage cams 28 after the latter have performed their clamping function, the cams 29 being swung in the direction indicated by the adjacent arrow, Figure 5, to lock cam levers 28 in clamping position, and in the reversed direction to permit said cam levers to be swung in the direction indicated by the arrow adjacent thereto, same figure, to relax the clamping pressure. The gages or walls are preferably provided with internal cleats 30, which are adapted to overlie grooved marginal portions of the form members (see dotted lines Figure 3), to guard against such members working upwardly when subjected to the pressure of the movable gages or walls.

When the forms are placed within this body, the clamping devices are swung upward into engagement with the respective socket plates, and the hooks engaged with the pivoted brackets. The clamping elements are then operated to clamp the form members together. After the casting or molding operation is completed and the cementsitious units are "set", the hooks are knocked loose to permit the clamping elements to be withdrawn and the clamping gages or walls removed preliminary to the dismantling of the form for the removal thereof and of the molded units.

From the above description, it will be apparent that I have produced a construction in which play is provided or accommodated between the gages or walls and the bottom of the body, which it has been demonstrated, is therefore susceptible of long and continuous service in the production of perfectly uniform and interchangeable concrete units or blocks, and while I have shown and described the preferred construction of the apparatus, it is to be understood that the right is reserved to make such changes as properly fall within the spirit and scope of the appended claims.

I claim:

1. A casting car, comprising a framework, an end and a side wall or gage supported in fixed relation to the framework, cross timbers upon the framework in a plane below that of the said walls or gages, a bottom secured to the cross timbers, and movable end and side walls or gages supplemental and respectively parallel to the first named end and side wall, and resting on said bottom.

2. A casting car, comprising a framework, an end and a side wall or gage supported in fixed relation to the framework, cross timbers upon the framework in a plane below that of the said walls or gages, a bottom secured to the cross timbers, movable end and side walls or gages supplemental and respectively parallel to the first named end and side wall, and resting on said bottom, and means carried by the framework for securing the respective movable end and side walls against outward movement.

3. A casting car, comprising a framework, ledger plates secured at one end and side of said framework, posts carried by the ledger plates, end and side walls or gages secured to the end and side posts respectively, cross timbers upon the framework in a plane below that of the said walls or gages, a bottom secured to the cross timbers, and movable end and side walls or gages supplemental and respectively parallel to the first named end and side wall, and resting on said bottom.

4. A casting car, comprising a framework, an end and a side wall or gage supported in

fixed relation to the framework, cross timbers upon the framework in a plane below that of the said walls or gages, a bottom secured to the cross timbers, movable end and

5 side walls or gages supplemental and respectively parallel to the first named end and side wall, and resting on said bottom

cam levers for applying force on the mov-

able end and side walls inward of the bottom, and cams for holding the cam levers against 10 movement tending to relax their pressure on said walls.

In witness whereof I hereunto affix my signature.

ERRETT S. RHOADS.
